Ames & Jones
ATTORNEY.

UNITED STATES PATENT OFFICE.

FRANK H. WHEELOCK, OF WASHINGTON, DISTRICT OF COLUMBIA.

GAS BURNER.

Application filed September 5, 1925. Serial No. 54,802.

This invention relates to gas burners for general use, and the principal object of my invention is to provide a burner the interior parts of which are freely accessible, thus adapting the burner to be readily and conveniently cleaned whenever it is necessary to remove carbon, grease or other deposits. Another object of my invention is to provide a burner having a top or cap portion which is freely removable from the burner body for the purpose described, and which at the same time has a tight sealing connection with the body against any possibility of the leakage of fuel between the meeting surfaces of the cap and body when said cap is applied.

Still another object of the invention is to provide a two-part sectional burner of the character described in which the burner body is coupled to a mixing tube from which it is adapted to be slipped off, whereby the burner sections are rendered readily removable from the fuel supplying means and from each other so as to allow the burner as a whole to be cleaned with the greatest possible ease and freedom.

Still another object of the invention is to provide a burner having means for securing in a simple and efficient manner a thorough admixture of the fuel elements before ignition and the burning of the fuel so as to reduce carbon deposits to a minimum and produce a flame of the greatest possible intensity.

The invention consists of the features of construction, combination and arrangement of parts, hereinafter fully described and claimed, reference being had to the accompanying drawing, in which:

Figure 1 is a side elevation of the burner.
Figure 2 is a top plan view thereof.

Figure 3 is a vertical section on the line 3—3 of Figure 2.

In the embodiment of my invention as herein disclosed, I provide a burner composed of a body or case section 1 and a top or cap section 2, the burner as a whole being generally of circular form, although any other suitable form may be employed. The body or base section 1 has a lower circular sleeve portion 3 of minimum diameter, an upper rim portion 4 of major diameter, and an intermediate tapering portion 5. At

the juncture of the portions 4 and 5 a horizontal shoulder 6 is formed, from the outer edge of which the portion 4 extends upwardly in the shape of a projecting flange. The cap section 2 comprises an annular body portion 7 open at its bottom and closed at its top by a crown wall 8. The upper portion of the body 7 is provided with an annular shoulder 9 whereby it is thickened, the lower half of the body below the line of the shoulder 9 forming a depending flange 10. The shoulder 9 and upper portion of the body 7 are of greater diameter than the wall 8 and between the upper peripheral edge of the shoulder 9 and the peripheral edge of the wall 8 the outer surface of the wall 7 is stepped or beveled, as indicated at 11, at a suitable angle to the plane of the cap body. Through this beveled portion of the burner are formed a plurality of jet openings 12, said openings extending upwardly and outwardly at oblique angles to the beveled portion 11 and tangential or eccentric to the axis of the burner. By this arrangement of the openings 12 the jets of flames or products of combustion from the burner will be caused to travel in a spiral path around and in a direction across the top of the burner, thus increasing the range of travel of the flames and products so that a vessel or utensil resting upon the burner or supported above the same will be more highly heated and a greater proportion of the available heat utilized and waste of heat materially reduced.

The burner body 5 is mounted upon a mixing tube or chamber 13, provided with an external annular supporting shoulder 14. The external surface of the upper end of the tube above said shoulder is smooth-surfaced and receives the sleeve portion 3 of the body 5 which snugly encompasses such portion of the tube and rests upon the shoulder 14. The portion 3 engages the smooth-surfaced upper end of the tube sufficiently tight to provide a close joint and yet sufficiently loose to adapt the burner to be slidably applied and removed. Below the shoulder 14 the lower end of the tube is externally threaded, as at 15, to receive an internally threaded hollow head or nuts 16 having air inlet openings 17 of a prescribed size. Fit-

ted in the bottom wall of this nut 16 is a gas supply nipple 18 internally threaded at its lower portion for engagement with a valved gas supply pipe or the like. Gas 5 entering through the nipple 18, having a passage of fixed dimensions, entrains with it air flowing through the openings 17, the air and gas passing upwardly through the tube 13 into the burner. The length of the 10 upper end of the tube 13 above the shoulder 14 is such that the upper end of said tube terminates close to and a short distance below the wall 8 of the cap 2. As a result, the air and gas entering through the tube 13 15 will strike the underside of the wall 8, acting as a baffle plate, causing the stream of air and gas to be impelled downward into the bowl-shaped chamber of the base 1 and to be thereby agitated and thoroughly 20 mixed therein before discharging through the jet apertures 12. Provision is thus made for securing, in a simple and effective manner, a proper combination of the air and gas constituents before ignition thereof in 25 order to secure a reduction of carbon deposits and to produce an intense flame.

By reason of the described construction of the burner body 1 and the tube 13, it will be seen that the burner as a whole has a 30 slip-connection with the upper end of the tube and may therefore be readily and conveniently applied or removed by simple endwise up and down movement, permitting of the assemblage of the parts and their 35 disassemblage in a quick, ready and convenient manner. Also it will be seen that by the detachable connection of the cap section 2 with the body 1, such cap section may be readily applied to the body and as readily 40 and conveniently removed therefrom. This permits of the cap section alone or of the entire burner being removed and its sections disassembled for the purpose of rendering the same easily accessible for the cleaning 45 out of carbon, grease and other deposits. In practice, the shoulder portion 9 of the cap section and rim edge of the flange 4 of the body are made smooth-surfaced for a ground joint engagement, so that, while the cap is 50 mounted so that it may be easily lifted off the body, a sealed joint will be provided which will be proof against the leakage of the fuel. The flange 10 is also preferably made of slightly less diameter than the internal diameter of the flange 4, allowing sufficient space for expansion of the wall 7 under the action of heat without liability of the cap section warping or becoming bound 55 upon the body section. The flange 10 may terminate above shoulder 4 or may extend down to and seat in said shoulder, as desired.

As shown, the stepped or beveled portion 60 11 of the cap section is preferably corrugated or fluted, forming riffles which agitate

and cause a thorough final mixture of the fuel constituents at the moment of ignition, thus further promoting thorough combustion of the fuel.

The construction of burner described ensures maximum simplicity, maximum efficiency in the mixing of the air and gas, so that an intense flame will be produced with a minimum liberation and deposit of carbon, and maximum convenience in the assemblage and disassemblage of the burner parts and in permitting access to such parts for the removal of deposits whenever required.

Having thus fully described my invention, I claim:

1. A gas burner comprising a hollow body open at its top and having a relatively contracted open bottom, a mixing tube extending through the open bottom of the body and above and below the same, said body 85 slidably engaging said tube and the latter having a shoulder intermediate of its length on which said body rests and by which it is supported, a burner cap mounted upon and closing the top of the burner body, said cap having a flange depending into the body below the upper end of the mixing tube, the latter extending into the space bounded by said flange and terminating below but in close proximity to the crown wall of said 95 cap, and fuel and air supplying means at the lower end of said tube.

2. A gas burner comprising a hollow body of inverted substantially frusto-conical form, and open at top and bottom, said body having an upwardly flaring mixing chamber, a horizontal flange extending outwardly at the top of said chamber and beyond the wall thereof, and a vertical flange rising from said horizontal flange, a burner cap having a horizontal flange resting upon the vertical flange of the body and a depending vertical flange depending inside and vertical flange of the body and disposed in spaced relation thereto and to the horizontal flange of the body, a mixing tube extending through the open bottom of the body and above and below the same, said tube having its upper portion projecting through the mixing chamber of the body and into the space bounded by the vertical flange of the cap and terminating at its upper end close to the crown wall of the cap, said tube slidably supporting said body and having a shoulder on which the body rests, and fuel and air supplying means connected with the lower end of said tube below the body.

3. A gas burner comprising a hollow body having an upwardly flaring mixing chamber, said body being provided with a body opening of less diameter than the chamber and a top opening of greater diameter than the chamber, said top opening being bounded by a vertical flange, a mixing tube slidably receiving the body and having a shoul-

der on which the body rests and is supported, said tube being threaded at its lower end below the shoulder and having its upper portion extending through the mixing chamber and into the space bounded by the vertical flange of the body, a burner cap loosely supported upon the body and having a horizontal flange resting on the vertical flange

thereof and a vertical flange depending inside the vertical flange of the body and receiving the upper end of the tube, and a head engaging the threaded lower end of the tube and provided with a vertical gas supply inlet and lateral always-open air inlets. 10

In testimony whereof I affix my signature.
FRANK H. WHEELOCK.
